UNITED STATES PATENT OFFICE.

FREDERICK GRINNELL, OF PROVIDENCE, RHODE ISLAND.

AUTOMATIC FIRE-EXTINGUISHER.

SPECIFICATION forming part of Letters Patent No. 399,521, dated March 12, 1889.

Application filed February 3, 1888. Serial No. 262,959. (No model.)

To all whom it may concern:

Be it known that I, FREDERICK GRINNELL, of the city and county of Providence and State of Rhode Island, have invented a new and useful Improvement in Automatic Fire-Extinguishers, of which the following is a specification.

The object of this invention is to protect the sensitive parts of an automatic fire-extinguisher from corrosion or accumulations of dirt, gum, &c.; and it consists of a protecting-cap fitted to the base of the extinguisher covering the valve and the heat-actuated device, the latter by being connected to both the cap and the valve through a lever fulcrumed on the base, or an arm projecting therefrom serving to hold both the valve and the cap to their respective seats. By this means I may utilize the fluid-pressure acting against the movable valve-seat as a force to hold the cap to its seat.

My invention also consists of minor improvements hereinafter described.

In the accompanying drawings, Figure 1 represents a sectional view through the center 25 of my improved extinguisher. Fig. 2 is a similar section taken on the line 2 2, Fig. 1.

The base or body of the extinguisher 1 is formed with a water-passage, 2, and is adapted to be screwed into a water-distributing pipe 30 in the usual manner. Around the periphery of the base I form a seat, 3, for the protecting-cap. The water-passage is closed by a valve, 4, and this valve may be secured to or form a part of a deflector in the usual way, and I prefer, also, to use in connection with this invention the flexible valve-seat 5, the flexibility of the seat operating to keep the port closed while the valve moves the short distance necessary to force the cap to its seat. 40 The valve is held closed against the fluid-pressure in the water-pipe by a strut, 6, bearing against the center of the valve at one end and the end of lever 7 at the other end. The said lever 7 is fulcrumed on a yoke, 8, secured to base 1 by pins 12, and the other end of the lever is held by a hook, 9, which may be secured to the cap 10 by any of the well-known heat-actuated devices.

In Fig. 1 I have shown the cap 10 as made 50 of glass with lugs 13 on its interior surface, and between these lugs I fasten a metallic anchorage-plate, 11, to which the hook 9 is

attached by a joint, 14, of fusible solder. Upon the occurrence of a fire in the vicinity of the sprinkler the solder melts and releases 55 the hook 9, whereupon the fluid under pressure in the pipes forces the valve from its seat, it being no longer restrained by lever 7, and the fluid passing into the cap exerts its full force to throw it off of its seat, thus allowing 60 the water to escape and extinguish the fire. The joint between the cap 10 and base 1 may be filled by a washer of paper or cloth saturated with paraffine or the like, or it may be simply greased over with any non-corrodible substance 65 that will melt at or below the operative temperature of the sprinkler.

In Fig. 2 I have shown a metallic cap, which may be painted on the outside to protect it from corrosion, and in places where dirt is 70 liable to accumulate it may be painted, as shown, so as to present the minimum amount of horizontal surface. In Fig. 2 the heat-actuated device 9 is fastened directly to the cap, and is formed of two pieces of metal—as, for 75 instance, brass and steel—which expand differently and which are fastened together, so that an abnormal increase of heat will cause it to bend out enough to release the lever 7 from the hook. In Fig. 2 I have also shown 80 a rigid valve-seat and an adjustable cap-seat, 15; but I may use both the flexible valve-seat and the adjustable cap-seat in the same device, the two together giving a greater nicety of adjustment than either alone would give. 85

When an extinguisher such as shown in Fig. 1 is screwed into the water-distributing pipe and the base properly painted, the risk of its failing to operate, even under the worst conditions, is exceedingly small. All the sensitive parts are completely protected from dirt or corrosion, the heat-actuated device is as far removed from the water as possible, the glass cap permits the radiant heat to have its full effect upon the parts designed to be released thereby, and finally the pressure in the pipes is brought into play, not only to hold both the cap and valve closed at normal temperatures, but also when released by the heat-actuated device to open the valve and throw 100 off the cap. This feature of the confined fluid passing into the cap and operating directly upon the said cap to throw it from its seat is an important one in a device of this charac-

ter, a slight sticking of the cap to its seat being easily overcome because of the extent of surface against which the pressure is exerted.

Where a rigid seat is used, as shown in Fig. 5 2, I prefer to have a spring—as, for instance, a plate-spring, 25—interposed somewhere in the device holding the valve. The plate-spring shown bears upon the valve, and has a notch in its upper surface in which the strut rests. 10 By this means the valve will be held to its seat by an elastic force, and the device will be rendered thereby less liable to leakage.

I claim—

1. In an automatic fire-extinguisher, the 15 combination of a valve closing the water-passage, a cap seated on the extinguisher and covering the valve, and a heat-actuated device inside the cap connecting the valve and the cap through a lever the fulcrum of which 20 is supported from the base of the extinguisher.

2. The combination of the base 1, having water-passage 2, valve 4, closing said passage, yoke 8, supported on the base 1, lever 7, fulcrumed on the said yoke, strut 6, between lever 25 7 and valve 4, cap 10, fitted to base 1 and inclosing the parts, as shown, and a device, as 9, connecting lever 7 to the cap and releasing both cap and valve when subjected to a temperature above the normal.

3. The combination of the extinguisher-base, having a water-passage, as shown, with an imperforate cap fitted air-tight to the base and inclosing between it and the base a valve covering the water-passage, and also inclosing 35 a reacting thermal device, the latter having a bearing on a fixture to the base and holding both the valve and the cap to their respective seats.

4. In an automatic fire-extinguisher, the 40 combination of the base with a non-corrodible cap seated thereon, a valve closing a passage through the base, and a heat-actuated device

secured to the inside of the cap, said device bearing against a support from the base, and a valve whereby the said device holds the 45 valve and the cap to their seats.

5. The combination of the extinguisher-body, having a water-passage closed by a valve, a flexible valve-seat for the valve, a cap seated on said body, and a heat-actuated device located entirely within the cap and holding the valve closed against its flexible seat, and also holding the cap to the body. 50

6. The combination of the extinguisher-body, having a water-passage and a valve for 55 closing the same, with a cap inclosing a heat-actuated device and the valve, the former having a support from the base and holding both the valve and the cap to their seats, and the said body having an adjustable seat for 60 the cap.

7. In an automatic fire-extinguisher, the combination, with the extinguisher-body, having a water-passage, as shown, and a valve closing such passage, of a heat-actuated device supported from the base controlling the valve, and an imperforate non-corrodible cap seated on the body and inclosing said valve and heat-actuated device, the said cap having secured to its interior surface a metallic 65 70 anchorage to which the said device is attached.

8. The combination of the extinguisher-body, having the water-passage, as shown, and a valve closing the same, a heat-actuated device supported from the base holding the valve 75 closed, and a glass cap seated on the base and inclosing the valve and heat-actuated device, the said cap having a metallic anchorage secured to its interior surface, to which the heat-actuated device is attached.

FREDERICK GRINNELL.
